NOZZLE FOR MACHINES FOR COATING
SHOE BOTTOMS

Wilbur L. MacKenzie, Beverly, Mass., assignor to
United Shoe Machinery Corporation, Borough
of Flemington, N. J., a corporation of New
Jersey

Application June 3, 1938, Serial No. 211,530

19 Claims. (Cl. 91—43)

My invention relates to nozzles for coating applying machines and is herein illustrated as embodied in a machine for applying an adhesive coating to shoe bottoms and specifically to the channels of shoe soles.

In coating the channels of the soles of welt shoes, a substantial change in the characteristics of these channels is found along the length of the channel. For example, a variation in the width of the channel is found between the forepart portion and the shank portion, thus rendering it desirable, when the cement is to be applied by an extruding nozzle, so to arrange the machine that these differences may be accommodated. Such a nozzle to be successful must also be arranged to apply a uniform coating both to the relatively flat forepart portions of the base of the channel and to the portions of curved and irregular contour found at the break of the sole at the ball line and in the shank portion. One satisfactory embodiment of a nozzle suited to meet these requirements is illustrated in Letters Patent of the United States No. 2,195,416, granted Apr. 2, 1940 up my copending application and is claimed in a divisional application Ser. No. 214,262, filed June 17, 1938. One object of this invention is to provide an improved form of nozzle for this purpose which will accommodate even greater divergencies in the character of the area to be coated and will apply a coating uniform both in thickness and in distribution.

In attaining this object, the nozzle comprises two sections, one of which is fixed and is arranged to apply a coating to the channel flap and a narrow adjacent portion of the channel base. The other section is a yieldable arrangement, embodying a plurality of tiltably mounted, spring-pressed delivery members, each one of which applies a narrow band of cement and is mounted to accommodate marked changes in the heightwise contour of the work.

In order that the nozzle may be arranged for coating both the narrow forepart portions and the wider shank portions, there is provided, in accordance with an important feature of the invention, an operator-controlled device for controlling, in a nozzle made up of a plurality of applying members, the fractional portion of those members which is being supplied with coating material. In its illustrated embodiment, this mechanism includes an operator-controlled valve arranged in one position to supply one portion of the applying members and in a second position, to supply another portion.

It is the practice of shoe manufacturers to vary

the shape and width of the shoe channel in different lots of shoes. Changes in style will account for part of the variations while changes in size account for an additional part. The usefulness of a nozzle for a machine of this type depends, therefore, to a considerable extent on its ability to be used for varying types of shoes. Accordingly, another feature of the invention resides in a novel arrangement, applicable where a plurality of delivery members is employed which may be divided into groups, and arranged to determine the number of delivery members in the respective groups. As illustrated, the nozzle has a plate provided with passages for supplying coating material to a number of delivery members and in which a removable member or plug is associated with this plate for determining the division of the members into groups.

These and other features of the invention will be described in the following specification, taken in connection with the accompanying drawings, in which

Fig. 1 is an angular view of the head of the machine, showing the novel nozzle mounted thereon and with the forepart of a shoe presented to the nozzle;

Fig. 2 is a fragmentary view, on a larger scale, of parts of the nozzle, showing in section the shank portion of a shoe presented to the nozzle;

Fig. 3 is a section taken heightwise of the yieldable portion of the nozzle along the line III—III of Fig. 13;

Fig. 4 is a plan view of the tube-supporting plate with a controlling plug therein;

Fig. 5 is an angular view of the plug removed from the tube plate;

Fig. 6 is an angular view showing the inner face of one of the plates forming the fixed portion of the nozzle;

Fig. 7 is a view of the inner face of the associated plate of this fixed portion of the nozzle;

Fig. 8 is an angular view of a fragment of the fixed portion showing the outlet slots therein;

Fig. 9 is a view of the other face of the plate shown in Fig. 7;

Fig. 10 is a detail view of the work-contacting end of one of the delivery members in the yieldable portion of the nozzle;

Fig. 11 is a vertical section through the nozzle block and the valve which controls the admission of cement thereto;

Fig. 12 is a side elevation of the valve, taken from the left of Fig. 11;

Fig. 13 is a section taken on the line XIV—XIV

of Fig. 11 through the auxiliary block and through the main block of the nozzle;

Fig. 14 is a phantom view showing, in dash lines, the outline of the nozzle parts and the valve attached thereto and showing, in full lines, the cement in the passages of the various nozzle parts, as if said cement were a solid material, and

Fig. 15 is a similar view on a much larger scale but including only the tips of the fixed and yieldable portions of the nozzle and illustrating the manner in which cement is applied to the channel in the shank portion of a shoe.

In Fig. 1, the nozzle is shown as mounted on a portion of a machine of the type illustrated in the above-mentioned Letters Patent No. 2,195,416. This machine comprises a frame 12 having an upper arm 14 at the outer end of which is supported a casting 15 having spaced horizontal brackets 16 between which is positioned the body 20 (Fig. 11) or main block 18 of the nozzle. This block 18 has overhanging portions 20 resting on the brackets and is clamped in position thereon by a double-armed lever 22 which is fulcrumed on the main block and has arms the rounded ends 26 of which are forced against the under side of the brackets 16 by a screw 25, the point of this screw being turned against a portion of the block 18 to clamp the nozzle in position on the machine. The nozzle has a fixed section or portion 30 (Fig. 2) for coating the inner surface of the upstanding flap c and an inner margin of the base of the channel in the sole of a shoe S. The point of this fixed nozzle portion rests at the root a of the channel, the sole of the shoe being held in a substantially horizontal plane as it is manipulated to carry successive portions of the channel past the nozzle. The nozzle also has a yieldable section or portion 31 arranged to deliver cement to the channel bed b which, around the forepart of the shoe, will have a substantially uniform width and will be approximately horizontal, while the corresponding channel bed b' (Fig. 2) at the sides of the shank portion of the shoe will be curved and somewhat inclined to the horizontal. It is in order to accommodate this change in the heightwise contour of the channel bed that the yieldable portion 31 is provided. Cement is supplied to the nozzle through a flexible pipe 92 from a receptacle (not shown) by pressure supplied by a suitable pump (not shown) and the admission of cement to the nozzle is controlled by a valve 95, the spigot 97 of which may be turned by an operator-controlled member, such as a treadle (not shown), through a jointed rod 108 having a forked portion which fits over a pin 109 extending through a passage 111 and crossing the forked end 113 (Fig. 11) of the spigot.

The presentation of successive portions of the channel to the nozzle may be effected manually with the assistance of a feed roll 122 mounted at the upper end of a shaft 124 which is received in a sleeve 134 slidable in an arm 126 tiltably mounted on the frame 12 of the machine. Adjustment of the position of the roll 122 with respect to the upper U of the shoe, so that it may be brought as closely as possible to the welt W without interfering with the nozzle, is effected by a hand lever 148 having a gear-and-rack connection (not shown) to the sleeve 134.

Inasmuch as the channel flap c is flexible and usually wrinkled and does not have the same relation to the sole of the shoe throughout its longitudinal extent, provision has been made for lifting the flap into co-operation with the outer side

of the fixed nozzle portion 30 by a vibratory contact finger 160. The mounting of this contact finger 160 is effected through a supporting arm 164 pivotally mounted on the casting 15 which is attached to the head of the machine. Pivotally mounted in this supporting arm is a carrier lever 168 provided with a holder lever 170 on which the contact finger 160 is adjustably mounted. This finger has a head 180, the end surface of which contacts with the outer surface of the channel flap. Vibration of the contact finger is effected, through a connecting rod 190 pivoted to an upstanding arm of the carrier lever 168, by a power-operated mechanism not herein shown. In order that it may be easier to present work to the machine, the supporting arm 164 for the flap-contacting finger is normally resiliently held away from the frame of the machine so that the head 180 of that finger is away from the fixed portion of the nozzle, thus allowing the flap c of the channel to be brought into position between the two. After the work has been positioned, the supporting arm 164 is drawn into operating position by mechanism (not shown) including a link 220.

The fixed portion 30 of the nozzle comprises co-operating plates 302 and 304, shown in Figs. 6 and 7, the faces of these plates being brought into contacting relation and the two plates being secured on the main block 18 by attaching screws 306 (Fig. 13). Cement for this fixed portion 30 is delivered through a passageway 308 in the main block 18, the end of which terminates in a conical recess 310 formed on the back side of the inner plate 304 which is provided with a hole 312 communicating with a groove 316 formed in the face 318 (Fig. 7) which lies in contact with the face 320 (Fig. 6) of the other plate 302. The lower portion 322 of the groove 316 is continued in a shallower portion 326 to the very tip of the plate 304. The co-operating plate 302, on the other hand, is provided along the lower end of its face 320 with a recess 328, so shaped that when the two plates are brought together, an outlet opening comprising an upright slot 330 and a bottom slot 332 will be formed. It will be noted also that the edge face of the plate 302 is cut away at 334 to prevent the cement from being scraped off the channel flap as the shoe is moved forward, i. e., away from the observer in Figs. 1 and 2 and in the direction of the arrow in Fig. 15.

Control of the quantity of the cement delivered to the fixed portion of the nozzle is rendered independent of the quantity delivered to the yieldable portion 31 of the nozzle by providing a valve member 340 having an enlarged portion 342 which is threaded in the block 18 and a reduced portion 344 smaller than the passageway 308 and provided with a conical tip 346 which may be brought closer to or farther away from the valve seat 310 by turning this rod and then locking it in position by a nut 348. The intermediate portion of the rod 340 fits the bore 308 and prevents back flow to the threaded portion 342.

For convenience of manufacture, the support for the yieldable portion 31 of the nozzle is an auxiliary block 350 which is held in position on the main block 18 by screws 352 (Figs. 1 and 13). This yieldable nozzle portion 31 is of the character illustrated in Letters Patent of the United States No. 2,177,666, granted Oct. 31, 1939, upon the application of W. L. MacKenzie and E. S. Nokes for Coating apparatus. It comprises a series of delivery members 354 (Fig. 3) which are tiltably mounted on a pivot rod 356.

within a fork 358 (Fig. 14) of this auxiliary block 350. Downward movement of these delivery members 354 is limited by engagement of the upper ends 359 (Fig. 3) thereof with a surface 360 formed at the inner end of a groove 362 in this block 350. The outlet ends of the delivery members are yieldably held in substantially flat contact with the work by a series of spring wires 364 having curved lower ends which rest in grooves 368 (Fig. 13) formed in the upper edge faces of the delivery members. The spring wires 364 are mounted in a removable supporting plate 368 held on the block 350 by screws 370. This mounting of the delivery members 10 allows the outlet ends to move up and down as the heightwise contour of the channel bed changes, the movement being substantially parallel to the outlet slot 330.

Each individual delivery member is provided 20 with a foot 372, the work-contacting face of which has parallel grooves 374 (Fig. 10), the sides of which are here shown as meeting at an angle of 60°. Under some conditions, a different angular relation of these ribs may be found preferable. Each foot 372 has a passage 376 forming a continuation of a tube-locating groove 378. In these passages 376 are received the lower ends of yieldable metallic tubes 380 having passages 381, the upper ends of the tubes being supported by a plate 382 attached to the auxiliary block 350 by screws 384. The tubes are held in the plate 382 by solder in a transverse groove 385. By reason of the inclined relation of the work-contacting face 386 of each foot 372 to the 30 axis of its passage 376, the outlet opening 388 has a heart shape and at the leaving end of the foot, a small projection 390 is found which tends to prevent, to a large extent, an excessive amount of cement from being extruded toward this leaving end of the foot, even though the work is not held in firm contact therewith. The tube-supporting plate 382 has a transverse bore 392 and small delivery outlet passages 394 connect the tubes 380 individually to this bore.

Attention has already been called to the fact 45 that the channel bed *b'* of the shank portion of the shoe is wider than the channel bed *b* of the forepart of the shoe. Accordingly, as shown by a comparison of Figs. 1 and 2, a less number 50 of delivery members is usually required in cementing the forepart of the shoe than in cementing the shank portion. The ratio between these widths varies in different types of shoes and, in order that a manufacturer may not be 55 forced to utilize a different nozzle for each different type of shoe, provision has been made for controlling the number of delivery members in use. To this end, a plug 400 is inserted in the bore 392 and is retained in position therein by 60 a finger nut 402 abutting the far side of the plate 382 and threaded into the plug 400 to hold it in position. At the near end of the plug, as viewed in Fig. 3, there is a head 404 (Figs. 4 and 5) notched at 406 to receive a dowel pin 407 which 65 keeps the plug from turning in the bore. Division of the tubes into two groups, one of which is sufficient for the forepart and both of which are needed for the shank portion, is effected by a partition 408 on the plug, lying between 70 notches 410 and 412. These notches constitute passageways to connect a certain number of the delivery outlet passages 394 in the plate to supply passages, to be described, and permit the user of the machine to render it suitable for another 75 style of shoe merely by removing the plug 400.

and inserting one of a different design. The plug shown in Fig. 5 is so designed that three tubes 380 are connected by the notch 410 to a supply passage open throughout the whole traverse of the shoe channel and that two additional tubes (making five in all) are connected by the notch 412 to another supply passage during the treatment of the shank portion of the shoe. To this end, cement delivered to the nozzle through the flexible pipe 92 is received in an upper passage 420 in the valve 95 and travels thence through a passage 422 (Figs. 11, 12 and 14) in the spigot 97 to a horizontal connection 424 and from there by outlet passages 426 and 428 to one or both of vertical supply passages 15 430 and 432, depending on the position of the valve spigot 97. The vertical passage 430 communicates directly with a corresponding passage in the nozzle block 18 and enters the lateral passage 308 surrounding the reduced portion 20 344 of the valve member 340. It moves thence by passages already described to the fixed portion 30 of the nozzle and also by a passage 434 (Figs. 3, 13 and 14) extending laterally from the passage 308 to one portion of the delivery 25 members by a horizontal bore 436 in the auxiliary nozzle block 350 and a groove 438 in the upper surface of the tube plate 382 which terminates in a short, vertical passage 440 (Fig. 4) communicating with the passageway formed by 30 the notch 410. The other delivery members, on the other hand, are supplied through the vertical valve passage 432 communicating with a passage 442 in the valve block 18. This passage 442 connects with a horizontal transverse passage 444 35 in the auxiliary block 350 terminating in a down passage 446 formed partly in the block 350 and partly in the plate 382 and terminating at a point opposite an inclined surface 450 on the plug 400. The inclination of this surface is such 40 that the adjacent periphery of the plug constitutes a stop to shut off certain of the delivery outlets 394 while, at the same time, the cement overflows into the passageway formed by the notch 412 and is thereby delivered to that extra 45 number of delivery members needed for the shank portion of the shoe. It will be observed that the tube plate 382 is made up to contain the maximum number of tubes and delivery members which may be required. When a smaller 50 number of tubes than this maximum is employed, plugs 452 (Fig. 4) may be inserted to close the outlets 394 which would normally feed these tubes. The plug 400 is so designed that the partition 408 will always be positioned between two of the outlets 394 and by supplying plugs of suitable design, any desired groups of delivery members may be employed.

A treadle (not shown) may be employed for turning the rod 108 connected to the spigot 97 60 of the valve 95. When no shoe is being presented, this spigot will be turned to an off position, not illustrated, where both passages 426 and 428 of the spigot are out of communication with the delivery passages 430 and 432. It may 65 also be turned to two operating positions, in one of which, as illustrated in Figs. 12 and 14, cement will be supplied to both delivery passages. In the latter position, a stop finger 460 on the valve spigot is in contact with a pin 462 on the casing of 70 the valve 95. In another intermediate position, the stop finger 460 then being as shown in dash lines, cement is supplied to only the vertical passage 430. Determination of this intermediate position may be by any suitable arrangement, such 75

- as a combination of a light and heavy spring (not shown), tensioned successively by a treadle (not shown) or a combination of treadles (not shown), one of which comes to a stop when it has brought 5 the spigot to the intermediate position and the other of which may be moved to carry the spigot finger 460 against the stop 462.
- For the sake of bringing the delivery members 354 of the yieldable nozzle portion 31 as 10 close as possible to the fixed nozzle portion 30, the plate 304, on its face opposite that shown in Fig. 7, is provided with a notch 327, shown in Figs. 1, 2 and 9. This plate is also relieved at 329 so that it will not bind in the base of the channel.
- 15 In the use of the machine, a shoe held by the operator in inverted, substantially horizontal position will be presented to the machine, the channel flap *c* being brought into engagement with the inclined side 331 of the fixed nozzle portion 30, which thereby serves as a gage, and the channel bed *b* brought into engagement with the yieldable nozzle portion 31, whereupon the rod 220 will be manipulated to bring the head 180 of the contact finger against the outside of the channel flap *c* and the feed roll 122 caused to 20 engage the upper of the shoe. At the same time, the valve spigot 97 will be turned to a position such as that shown in Figs. 12 and 14 in order to render active both groups of delivery fingers 25 of the yieldable nozzle portion 31 by supplying cement thereto. Progressive movement of the shoe in the hands of the operator to carry successive portions of the channel past the combined nozzle will be effected with the aid of the feed roll 122 while, at the same time, the work 30 position is gaged by bringing the root *a* of the channel against the tip of the fixed nozzle portion 30. As the coating action progresses from the heel end toward the toe of the shoe, the operator will change the position of the valve spigot 35 40 45 50 55 60 65 70 75 97 as the ball line is encountered to reduce the number of delivery members in use and hence the width of the band applied and will proceed to cement the channel around the forepart of the sole. When the ball line is again encountered on the other side of the shoe, the spigot 97 must be turned back to the position shown in Fig. 14 so that the channel bed *b'* of the shank portion on the other side may be cemented. The operator is thus enabled to effectively apply a uniform and continuous coating to the shoe channel, both to the inner side of the channel flap and to the adjacent channel base. The utilization of a rigid metallic nozzle for coating the inner face of the channel flap, and which may be seated in the root of the channel, makes it easy for the operator to bring the shoe into the desired relation to the other elements of the machine and provides an abutment against which the flap may be intermittently pressed by the head 180 of the contact finger. At the same time, a uniform and continuous coating will be applied to the base of the channel, regardless of its particular contour at any point, and this is done by a metallic nozzle which is unaffected by the coating materials employed, is readily cleaned and the width of which is controlled by the valve 95 as the width of the channel base varies around the shoe. The effective extruding of viscous coating materials depends quite extensively on the maintenance of the outlet portion of the nozzle in firm and substantially flat contact with the surface of the work. This degree of firm contact with the work is readily obtained by the series of pivotally mounted, narrow delivery members, each one of

which is spring pressed heightwise toward the work with its outlet end substantially always flat against the base of the channel.

Having thus described my invention, what I claim as new and desire to secure by Letters 5 Patent of the United States is:

1. In a machine for coating shoe bottoms, a nozzle comprising a fixed section for coating one portion of a piece of work and a yieldable section made up of a series of yieldable members having 10 delivery openings for coating an adjacent work portion, the surface characteristics of which vary as the coating is applied along the work.

2. In a machine for coating shoe bottoms, a nozzle comprising a supporting body, a nozzle 15 section fixed against movement on the body for applying a band of coating material and a nozzle section made up of a plurality of delivery members arranged side by side for individually applying bands on the work adjacent to the band 20 coated by the fixed section, the outlet ends of said members being mounted for bodily displacement.

3. In a machine for coating channels having a flap and a base, a nozzle comprising a fixed section having elongated outlet openings through adjacent surfaces thereof to coat the channel flap and an adjacent portion of the channel base, said nozzle also having a series of hollow yieldable delivery members through the passage of which 30 a coating is applied to substantially the remainder of the width of the base of the channel.

4. In a channel-cementing machine, a nozzle comprising a fixed section having an upright outlet slot for applying cement to the attaching face 35 of the channel flap and a yieldable section comprising a series of hollow delivery members the work-engaging ends of which are movable heightwise in a direction substantially parallel to said outlet slot and are arranged thus to accommodate changes in the contour of the bed of the channel.

5. In a channel-cementing machine, a nozzle comprising a delivery member the work-engaging foot of which is provided with parallel grooves, 45 said member having an outlet passage intersecting said grooves at an acute angle to their length and leaving an intermediate projection between the grooves at the leaving end of the foot.

6. In a cementing machine, a delivery member 50 having a work-engaging foot adapted to rest on the work, the work-engaging surface of said foot being provided with grooves extending in the direction of relative traversing movement between the work and the nozzle, said grooves being 55 formed by intersecting plane surfaces, and a passage supplying coating material to said grooves and intersecting the sides of the grooves wholly between the ends thereof.

7. In a machine for coating shoe bottoms, a nozzle comprising a plurality of delivery members adapted to be divided into groups, means provided with a plurality of passages for supplying coating material to said groups of delivery members and interchangeable passage-controlling means for determining the number of delivery members in the respective groups.

8. In a machine for coating shoe bottoms, a nozzle comprising a plurality of delivery members adapted to be divided into groups, and means for supplying coating material to said groups of delivery members comprising a fixed member provided with passages and a removable member associated therewith for determining 70 75 80 85 90 95

the number of delivery members in the respective groups.

9. In a machine for coating shoe bottoms, a nozzle comprising a plurality of delivery members, a fixed member having more than one supply passage, said member having a transverse bore intersecting said passages, a series of delivery outlets communicating with said bore and leading to the delivery members, and a plug for insertion in said bore and having separated relieved portions to connect the supply passages with predetermined delivery outlets.

10. In a machine for coating shoe bottoms, a nozzle comprising a plurality of delivery members, a fixed member having more than one supply passage, said member having a transverse bore intersecting said passage, a series of delivery outlets communicating with said bore and leading to the delivery members, and a plug for insertion in said bore and having separated relieved portions to connect the supply passages with predetermined delivery outlets, one of said relieved portions being arranged also to close part of the delivery outlets.

25 11. In a machine for coating shoe bottoms, a nozzle comprising a supporting member having two supply passages, a plurality of delivery members movably mounted thereon in side by side relation, said supporting member having a plurality of tubes for carrying coating material to said delivery members, outlets in the delivery members communicating with said tubes, and a removable member providing passage-forming means for connecting a certain number of said outlets to one of said supply passages and some more of the outlets to the other supply passage.

12. In a machine for coating shoe bottoms, a supporting member, a plurality of delivery members associated therewith, said supporting member having two supply passages and individual outlet passages communicating with said delivery members, and removable means having a stop for shutting some of said outlet passages and having passageways connecting the other outlet passages to one or the other of the supply passages.

13. In a machine for coating shoe bottoms, a nozzle having a series of delivery members, a supporting member therefor having a series of adjacent outlet passages communicating with said delivery members, said supporting member hav-

ing a plurality of supply passages and a bore intersecting said outlet passages and said supply passages, and a plug adapted to be inserted in said bore for connecting part of the outlets to one of the supply passages, said plug having a partition separating adjacent outlet passages of the series.

14. In a machine for coating shoe bottoms, a nozzle having a plurality of applying members, means for supplying coating material thereto, and operator-controlled valve means associated with said supplying means for determining the number of the applying members to which coating material is supplied.

15. In a machine for coating shoe bottoms, a nozzle having a plurality of applying members, and an operator-controlled two-position valve arranged in one position to supply one portion of said members and in a second position to supply another portion.

20 16. In a machine for coating shoe bottoms, a nozzle comprising a fixed section and a yieldable section for coating a band along the work, and operator-controlled means for varying the width of the band of cement applied by said yieldable section.

25 17. In a machine for coating shoe bottoms, a nozzle comprising a fixed section and a section made up of a series of yieldable delivery members only part of which are normally active, and operator-controlled means to render active additional members during the progress of the work-traversing movement.

18. In a machine for coating shoe bottoms, a nozzle having a plurality of applying members, and an operator-controlled valve arranged in one position to supply one portion of said members and in another position to supply both this portion and another portion of the members.

30 19. In a channel-cementing machine for coating a channel flap and a channel base, a nozzle having a flap-coating section and a base-coating section, the latter being made up of a plurality of delivery members, and an operator-controlled valve arranged in one position to supply the flap-coating section and a part of the delivery members and in a second position to supply these and an additional part of the delivery members.

WILBUR L. MACKENZIE. 50
